(57) **CLAIM**

The ornamental design for a wireless voice media gateway enclosure, as shown and described.

DESCRIPTION

FIG. 1 is a front perspective view of the wireless voice media gateway enclosure.

FIG. 2 is a front elevation view of the wireless voice media gateway enclosure.

FIG. 3 is a rear elevation view of the wireless voice media gateway enclosure.

FIG. 4 is a right side elevation view of the wireless voice media gateway enclosure.

FIG. 5 is a left side elevation view of the wireless voice media gateway enclosure.

FIG. 6 is a top view of the wireless voice media gateway enclosure; and,

FIG. 7 is a bottom view of the wireless voice media gateway enclosure.

The enclosed broken lines immediately adjacent the claim represent the bounds of the claimed design while all other

(Continued)

broken lines are directed to environment and are for illustrative purposes only; the broken lines form no part of the claimed design.
